Filed Aug. 7, 1961, Ser. No. 129,745
5 Claims. (Cl. 20—62)

This invention relates to shutters, and particularly to improved methods for constructing same.

Conventional shutters consist of elongated side members which are joined together by transversely disposed end members, which side and end members provide a frame which defines an area therebetween which contains various types of inserts such as paneling, screening or a plurality of movable louvers.

The side and end members are conventionally joined together by butting and gluing the flat opposing edges thereof wherein the glue is applied to the opposing surfaces to be joined after which the members are pressed and held together until the glue hardens and a suitable joint has been effected therebetween. This frequently results in the glue being expressed or squeezed out from between the abutting faces of the members onto the exposed outer faces of the members adjacent the joint with the glue thus expressed from between the joints marring the appearance of the shutters, particularly when appearing on the front or top face of the shutter. As a result, the manufacturer of the shutters is put to the inconvenience and additional labor and expense of carefully inspecting each of the shutters and removing this glue exposed to view on the faces of said members which increases his cost of operation and the cost of the shutters to the purchaser.

The expressed glue usually sets before it can be removed and adheres strongly to the wood, thereby making it difficult to remove and may result in defacing of the exposed surface during removal thereof or pitting due to small portions of the wood being removed with the glue, depending on the means employed to effect removal of the glue.

Furthermore, in many conventional shutter structures the top marginal edges of both members at the joint therebetween are normally exposed to view and any flaw or defects in the edge portions of the abutting members is exposed to view further detracting from the appearance thereof and requiring a higher degree of finishing of the abutting edges of the members prior to their being joined together. Also, when shutters of this type having an exposed joint between the side and end members are subjected to repeated expansion and contraction due to repeated changes in temperature and humidity conditions during use, the members become separated thereby presenting to view an undesirable spacing between the members.

In addition, in conventional louvered shutters, the construction is such that when the louvers are completely closed, a space remains between the marginal edge of the end-most louvers and the opposing marginal edges of the end members of the frame, through which light can escape.

Therefore, an object of this invention is to provide a novel method of constructing shutters which eliminates the aforementioned problems and results in a shutter which is more attractive in appearance and of sounder construction than shutters presently available.

Still another object is to provide a method of constructing shutters which prevents the glue from being expressed onto the outer face of the jointed members, which provides a concealed joint between the members which conceals any flaws in the edges of the butted members and thereby reduces the degree of finishing required on such

2

edge portions and which reduces the amount of inspection required at the point of manufacture.

Still another object is to provide a joint between the members of a shutter in which any spacing between the members caused by separation thereof due to ambient temperature and humidity conditions will be concealed from view.

Still another object is to provide a shutter construction with a novel type of concealed joint which will prevent unpainted or unstrained portions of the jointed members from becoming exposed to view if separation should occur after painting or staining thereof.

Still another object is to provide a novel louvered shutter which eliminates any undesirable exposed spacing between the end members and the louvers.

These and other objects and advantages of my invention will more fully appear from the following description made in connection with the accompanying drawings wherein like reference characters refer to the same or similar parts throughout the several views, and in which:

FIG. 1 is a front elevational view of a shutter of this invention;

FIG. 2 is an end plan view of FIG. 1;

FIG. 3 is a transverse section on an enlarged scale taken along the line 3—3 of FIG. 1;

FIG. 4 is a longitudinal section on an enlarged scale taken along the lines 4—4 of FIG. 1; and

FIG. 5 is a detail view on an enlarged scale of a portion of the joint shown in FIG. 3.

Reference is now made to the accompanying drawings for a more detailed description of my invention. The shutter shown in the drawings comprises a frame formed by a pair of elongated side members 10 and a pair of end members 11 and 12 which are joined to the side members in edge abutting relationship. The central area defined by said frame is provided with a plurality of elongated transversely disposed louvers 13 which are hingedly connected to the side members by means of the laterally extending hinge pins 13' which are journaled in the sockets 10a provided in the lower inner edge portions of the side members. All of the louvers are operatively connected to an elongated longitudinally movable operating rod 14 for simultaneous opening and closing movement of the louvers. A recess 11a is provided in the top face of the upper end member 11 for receiving the adjacent end of the operating rod when the louvers are fully closed and the rod has reached the limit of its upward travel.

The inner edge of each of the side members 10 is provided with an elongate concave groove or cove 15 which extends the full length of each of the side members. The side members are also provided with an elongate outwardly rounded or convexed ridge or strip 16 which protrudes from the side members and also extends the full length thereof. The top of the ridge terminates a short distance below the top or front surface 10b of the side members and is connected therewith by the vertical wall portion 10c to provide an elongate shallow recess in the inner front marginal edge of the side members which adds materially to the finished appearance of the shutter. The underside of the ridge merges or joins with the upper edge of the cove to define a groove for receiving the end members to join the end and side members together.

The top of the abutting edges of the end members 11 and 12 are each provided with laterally extending tongue portions 17. The top surfaces of the tongues are co-extensive with the top or front surfaces 11b and 12b of the end members and constitute continuations thereof. The underside 17a of the tongues are convexly curved to the same curvature as the covés 15 for mating abutting engagement therewith. The tongues are seated

in the grooves formed by the coves 15 and ridges 16 in close fitting relationship therewith, thereby joining the end side members together, the members being held together by glue disposed between the interfaces of the cove and tongue and between the lower portion 10d of the side members and the lower portion of the end members abutting therewith. The top marginal edge portion 17b of the tongue underlies and is overlapped by the ridge 16 and is preferably in engagement with the rear portion of the underside thereof to form a sealing relationship therebetween to prevent glue escaping unto said top marginal edge portion.

Thus, when the glue is applied to the mating surfaces of the cove and the convex portion of the tongue, and the side and end members are press fitted together, the close fitting relationship between the upper marginal edge portion of the tongue and the ridge effects a seal which substantially prevents any glue from being expressed from between the mating surfaces onto the top surface of the end members.

Furthermore, should any minute amounts of glue accidentally seep through onto the top marginal edge portions of the tongue, it is confined to the area immediately adjacent the marginal edge of the tongue and is overlain and concealed by the ridge and, therefore, does not have to subsequently be removed since it cannot be seen and does not mar the appearance of the shutters. The concealment of the marginal edge portion of the tongue by the overlapping ridge member is also of importance because it conceals any minor flaws or defects in the marginal edge portion such as minor chipping and the like. If this marginal edge portion were exposed to view in the finished product, these flaws and defects would mar the appearance thereof resulting in a lower quality product and if the manufacturer desired a higher quality product, he would be required to perform a more accurate finishing operation on said marginal edge portions of the end members.

The upwardly and outwardly curved underside 16a of the ridge also provides an important advantage because it enables the paint or stain applied to the shutters after assembly to penetrate and cover most of the top marginal edge portion 17b of the tongue overlain by the ridge. Thus, if the side and end members become slightly separated during use due to repeated expansion and contraction caused by ambient temperature and humidity conditions, no unpainted or unstained portion will appear to view as would be the case if the underside of the ridges were flush with the top surface of the tongue throughout the entire extent thereof. In addition to the important features previously recited, the rounded overlapping ridge also materially improves the appearance of the shutters and the cooperation of the ridge with the tongue provides a strong durable structure.

It will also be noted that the lower portion 10d of the inner edges of the side members extends beyond the ridges 16. Thus, the unoccupied portions of the coves 15 intermediate the end members are exposed to view when seen from the front, the ridges and coves combining to provide a unique and attractive appearance heretofore not available.

Attention is next directed to the construction of the inner edge portions of the end members 11 and 12 (best seen in FIG. 4) to prevent undesirable spacing and escape of light between the end members and the upper and lower louvers 13a and 13b respectively when the louvers are completely closed. The front inner marginal edge of the bottom end member 12 is provided with a curved groove or cove 18 similar to the coves 15 which extends the full length of the end member so as to cooperate with the coves 15 and the cove on the other end member 11 to provide a continuous coved frame about the louvers which substantially improves the appearance of the shutters. The back inner marginal edge of the bottom end member 12 is also provided with a curved groove or

5 cove 19 which also extends the full length of the end member and provides a recess for receiving the lower end of the lower louver 13b when the louvers are completely closed. Thus, when the louvers are completely closed, the lower end of the bottom louver 13b is disposed below and overlaps the top marginal edge 20 of the bottom end member so as to prevent any vertical spacing therebetween and the escape of light.

10 The lower edge portion of the top end member 11 has a curved groove or cove 21 formed in the front marginal edge thereof which extends the full length of the end member and cooperates with the coves 15 in the side members and the cove 18 in the bottom end member to provide a coved frame about the entire circumference 15 of the louvers. The back lower marginal edge of the top end member 11 is provided with a depending lip 22 which is designed and adapted to extend below the top marginal edge of the top louver 13a when said louver is completely closed. Thus, the lip 22 and the top marginal edge portion of the louver 13a overlap each other when the louvers are closed and prevent undesirable spacing between the louver and the end member and the escape 20 of light from therebetween.

25 Thus, from the foregoing, the advantages of this invention are readily apparent. The curved overlapping ridge conceals the joint between the side and end members and the top marginal edge of the end members; cooperates with the laterally extending tongue of the end members to seal the joint between the mating surfaces of the side and end member and prevent the escape of glue therebetween onto the front surface of the end member; conceals any glue which might escape onto the marginal edge of the tongue of the end member, and also conceals any flaws or defects in the marginal edge portion of the tongue. The curved nature of the underside of the overlapping ridge prevents unsightly unpainted portions of the marginal edge of the tongue from appearing if the sides and members become slightly separated during use. The curved overlapping ridge by itself and in combination with the coving framing the louvers materially contributes to the appearance of the shutters and sharply distinguishes them from shutters presently available, and the inner edge construction of the end members eliminates undesirable spacing relative to the closed louvers.

30 45 It will, of course, be understood that various changes may be made in the form, details, arrangement and proportions of the various parts without departing from the scope of my invention.

50 55 What I claim is:

1. Frame structure which includes two frame members joined together in edge abutting relationship, one of said members having a portion extending laterally from its abutting edge portion in overlapping relationship to the abutting edge portion of the other member, said last named abutting edge portion being an extension of an outer face of said other member, said face being exposed to view in the finished article embodying said frame structure, the underside of said overlapping portion which communicates with the marginal edge thereof and is opposed to said face being in spaced apart relationship therewith.

2. The structure of claim 1, wherein a portion of the underside of the overlapping portion engages said outer face of said other member.

3. Frame structure which includes first and second frame members joined together in edge abutting relationship, said first member having an outer face which is exposed to view in the finished article embodying said frame structure, said second member having a groove formed in the abutting edge portion thereof, said first member having a tongue portion seated in said groove, one side of said tongue being a continuation of said outer face of said first member, said tongue and outer face having a common marginal edge, the abutting side of said second member having a portion which overlaps and conceals

said marginal edge and engages said outer face, a portion of the underside of said overlapping portion which communicates with the outer edge of said overlapping portion and is opposed to said outer face being spaced from said outer face.

4. A shutter frame comprising elongate side members and transversely disposed elongate end members, the ends of which are in edge abutting relationship with the inner edges of said side members, said inner edges of said side members having an elongate inwardly facing cove formed therein extending longitudinally of said side members, said end members having flat outer faces exposed to view in the finished article embodying said frame, the ends of said end members having tongue portions extending outwardly therefrom and seated in said coves, one side of said tongue portions being a continuation of said outer faces of said end members, said tongues and their respective outer faces having a common marginal edge, the undersides of said tongues being convexed to substantially the same curvature as the coves in which they are seated so as to abut therewith, said side members having elongate inwardly and longitudinally extending ribs which overlap and conceal said marginal edges of said end members, the inner end portions of the undersides of said ribs engaging said outer faces of said end members, the outer end portions of the undersides of said ribs which communicate with the outer edge of said ribs being spaced from said outer faces.

5. A shutter having a frame consisting of elongate side members and transversely disposed end members, the outer ends of said end members being in edge abutting

relationship with the inner edges of said side members, said inner edges of said side members having an elongate groove formed therein extending the full length of said members and defined by opposed spaced apart inner edge portions of said side members, the abutting edges of said end members having laterally extending tongue portions, one side of which constitutes a continuation of one of the faces of said end members, said tongues being seated in said grooves in close fitting relationship therewith whereby the marginal edge portion of said one side of said tongue is overlapped and concealed by one of said inner edge portions, the marginal edge of said overlapping inner edge portion being set back from the marginal edge of the other inner edge portion whereby the interior of said grooves unoccupied by said end members are exposed to view when said shutters are viewed directly from the side thereof on which said overlapping inner edge portion is located, and wherein the rear portion of the underside of said overlapping inner edge portion is in sealing engagement with said tongue and a portion of the underside of said overlapping inner edge portion communicating with the marginal edge thereof and opposed to said end member is spaced from said end members.
